SURFACE FINISHING MACHINE
William C. Burt, Olean, N.Y., assignor to Clair
Manufacturing Co., Inc., Olean, N.Y.
Filed Oct. 11, 1962, Ser. No. 229,952
2 Claims. (Cl. 51—84)

This invention relates to improvements in surface finishing machines of the type variously known as buffing, polishing, glazing machines, or the like. Such machines are particularly adapted to surface-process workpieces such as flatware, hand tools, industrial jewelry, decorative hardware, and the like. Thus, the invention relates to machines of the type disclosed for example in earlier U.S. Patents 2,269,311 and 2,458,708.

One object of the present invention is to provide in a machine as aforesaid, in combination with a space-adjustable double roll arrangement, an improved roll pressure regulating means; thus providing a machine of improved functional characteristics which at all times submits the workpieces to uniform roll pressures, in combination with a quick and positive roll opening and closing arrangement.

Another object is to provide in a machine as aforesaid, an inexpensive and trouble-free and otherwise improved roll pressure regulating system.

Other objects and advantages of the invention will appear from the specification hereinafter and the accompanying drawing wherein:

FIG. 1 is a fragmentary top plan view of a machine embodying the invention;

FIG. 2 is a sectional view of the machine taken on line II—II of FIG. 1; and

FIG. 3 is a view corresponding to FIG. 2 but showing the machine rolls in "open" position.

The drawings herewith illustrate the invention as being employed in a machine of the general type shown in my earlier Patent No. 2,458,708, and deals with an improvement in that portion of the machine mechanism which is shown in FIG. 3 of the patent. Thus, as illustrated in the drawing herewith, the machine includes a base or frame 10 supported by legs 12 to a convenient height; frame 10 in turn supporting the oscillating workpiece carriage and the polishing or glazing rolls, and other mechanisms for driving and controlling the carriage and rolls as explained in Patent No. 2,458,708.

The rolls are indicated at 14—16; the roll 14 being mounted above the roll 16, and the rolls will of course be formed of any suitable material treated in any desired manner according to the character of the work to be done. The roll 14 is carried upon a shaft 18 while the roll 16 is carried upon a shaft 19.

The shaft 18 is journaled at its opposite ends upon rocker arms 20 which extend from opposite ends of a rocker shaft 24; the shaft 24 being in turn rotatably supported by means of pedestals 26 which extend vertically from opposite ends of the base plate 10. A second rocker shaft 30 is similarly journaled upon the pedestals 26 so as to extend parallel to the rocker shaft 24 and therebelow. Rocker arms 32 extend from the rocker shaft 30 in parallel relation and carry at their outer ends the lower roll shaft 19 in journaled relation thereon. The rocker shaft 24 is fitted with rearwardly extending crank arm 40 carrying a screw block 44. The rocker shaft 30 carries a crank arm 45 which terminates in a ball bearing 46 having a vertical slide aperture therethrough. A hydraulic cylinder member 48 is suspended from its upper end to the bearing 46 and slidably mounts therein a piston 50 which is fixed upon the lower end of a screw 52 which extends upwardly through the head of the cylinder 48 and thence through the slide bearing 46 and thence through the nut 44 which it engages in screw-thread relation. At its upper end the screw 52 carries a hand wheel 56. As in the case of the

2

earlier patents referred to, the rocker shafts are geared together by means of spur gears as indicated herein at 57. Hence the cylinder piston unit 48—50 is operable to force the rocker crank arms to swing the rolls apart so as to "open" the rolls 14—16 such as to the positions thereof shown in FIG. 3. Also, it will be appreciated that the hand wheel 56 is manually adjustable for purposes of regulating the distance between the rolls under operating conditions, so as to suit the machine to different classes of work.

In accord with the present invention the shaft 30 also carries a second crank arm 58 from which is suspended a counterweight 59 for angularly adjusting the attitude of the arms which carry the rolls 14—16. Thus, the hanging of an appropriate weight upon the arm 58 will impose upon the rolls 14—16 any desired "closing" and "working" pressure, assuming the cylinder-piston unit 48—50 to be idle. To vary this pressure, the weight may be adjusted longitudinally on the arm 58.

Motors as indicated at 60 are coupled to the rolls 14, 16, respectively, as by means of flexible belts or the like as indicated at 64. The work mounting carriage portion of the machine is illustrated herein to comprise a table 70 which is mounted upon the base plate 10 by means of slideways so that the table 70 is reciprocable horizontally in directions transverse to the rolls 14—16. Suitable means (not shown) may be provided to cause the platform 70 to reciprocate toward and away from the rolls 14—16, as shown in Patent No. 2,458,708. A second platform 80 is reciprocable relative to the platform 70 in directions axially of the rolls 14—16 independently of reciprocation of the platform 70, and suitable means (not shown) may be provided to cause the platform 80 to reciprocate in side-wise directions independently of backward and forward reciprocations of the platform 70. The platform 80 receives in slide-fitting relation thereon a work carrying plate 124. Thus, a gang of workpieces may be clamped upon the plate 124, as by means of any suitable detachable holders so that the workpieces are mounted to extend therefrom into position between the rolls.

It will of course be appreciated that whenever a batch of workpieces is finished and the operator actuates the "roll open" valve 126 as explained for example in Patent 2,458,708, the oil pressure enters the top of cylinder 48 and forces the piston 50 to lower the rod 52, thereby opening the rolls against the pull of the weight 59. This arrangement is good because the hydraulic mechanism provides a positive and quick-acting roll opening control which speeds the over all operation. However, when the oil pressure is released and the control valve diverted to the "return" conduit, the counterweight 59 is thereby freed to provide a uniform roll pressure against the work, as explained hereinabove.

It will be understood that whereas only one specific form of the invention has been illustrated and described in detail hereinabove, various changes may be made without departing from the spirit of the invention or the scope of the following claims.

I claim:

1. In a workpiece surface finishing machine, in combination,
  - a frame,
  - a pair of horizontal rocker shafts journaled in said frame in vertically spaced parallel relation to each other,
  - a pair of rocker arms fixed to each rocker shaft in longitudinally spaced relation thereon, each such pair of rocker arms projecting generally horizontally from its associated rocker shaft whereby the free ends of the rocker arms fixed to one rocker shaft are spaced above the free ends of the rocker arms fixed to the other rocker shaft,

a pair of surface finishing rolls, one being journalled between the free ends of one pair of rocker arms and the other being journalled between the free ends of the other pair of rocker arms,
 means for rotatably driving said surface finishing rolls, 5
 a crank arm fixed to each rocker shaft and each projecting generally horizontally from its associated rocker shaft whereby the free ends of said crank arms are in spaced vertical registry,
 gear means interconnecting said rocker shafts whereby 10
 the rocker shafts are constrained to rotate in relatively opposite directions,
 a nut member rotatably carried by the free end of one of said crank arms,
 a double-ended cylinder rotatably carried by the free 15
 end of the other crank arm,
 a roll spacing screw having a threaded portion engaged with said nut member and having a piston disposed within said cylinder,
 means for selectively pressuring said cylinder on one 20
 side of said piston to rotate said rocker shafts in a direction to move said surface finishing rolls apart,

and means for causing said surface finishing rolls to impose a predetermined pressure upon a workpiece disposed therebetween, in which such pressure is substantially completely independent of the roll spacing as effected by said roll spacing screw, the last mentioned means comprising a second crank arm fixed to the lower of said rocker shafts and projecting horizontally therefrom in a direction opposite to said rocker arms which are fixed to such rocker shaft, and a weight carried by the free end of said second crank arm.

2. In a machine as defined in claim 1 wherein said weight is longitudinally adjustable along said second rocker arm.
